(57) **CLAIM**

The original ornamental design for a lower body garment gusset panel with heart shape, substantially as shown and described.

DESCRIPTION

FIG. 1 is a top rear perspective view of a lower body garment gusset panel with heart shape of the present invention, as it may be used in an undergarment (the broken lines shown on the lower body garment gusset panel with heart shape and on the undergarment represent unclaimed features); and, FIG. 2 is a plan view of the claimed lower body garment gusset panel design.
